UNITED STATES PATENT OFFICE.

HENRY B. SWANTUSCH, OF THREE RIVERS, MICHIGAN.

V-BLOCK.

1,119,470.

Specification of Letters Patent.

Patented Dec. 1, 1914.

Application filed August 12, 1913. Serial No. 784,430.

To all whom it may concern:

Be it known that I, HENRY B. SWANTUSCH, a citizen of the United States, residing at Three Rivers, in the county of St. Joseph, State of Michigan, have invented 5 certain new and useful Improvements in V-Blocks; and I do hereby declare the following to be a full, clear, and exact description of the invention, such as will enable others skilled in the art to which it appertains to make and use the same.

This invention relates to a jig and has special reference to a V-block of novel construction and a jig made from several of 5 such blocks.

The principal object of the invention is to provide an improved form of V-block especially adapted for use in drilling cylindrical bodies such as shafts.

A second object of the invention is to provide a novel construction of jig made from several of such blocks.

With the above and other objects in view the invention consists in general of certain 5 novel details of construction and combination of parts hereinafter fully described, illustrated in the accompanying drawings, and specifically claimed.

In the accompanying drawings, like characters of reference indicate like parts in the several views, and Figure 1 is a front elevation of a V-block constructed in accordance with this invention. Fig. 2 is a side elevation thereof. Fig. 3 is a plan view of such a block. Fig. 4 is a section on the line 4—4 of Fig. 2. Fig. 5 is a plan view of a block used when the holes to be drilled are close together. Fig. 6 is a view of a jig constructed from several of these blocks. Fig. 7 is a section on the line 7—7 of Fig. 6. Fig. 8 is a section on the line 8—8 of Fig. 6.

In the V-block constructed in accordance with this invention there is provided a body 10, preferably rectangular in form and having on its upper and lower faces V-shaped grooves 11, one of these grooves being larger than the other. Through the body parallel to the grooves extends an opening 13 for purposes hereinafter to be described. Extending from the front of the block into the opening 13 is a set screw 14. Extending vertically of the rear face of this block is a dove-tail groove 15 wherein is mounted a slide 16 having bevel edges 17 one of which fits against the side of the groove. This slide is of less width than the groove 15 so

that take up shoes 18 may be inserted for the purpose of taking up any lost motion in the fit of the slide in said groove. These shoes are held in adjusted position by 60 machine screws 19 extending diagonally through the material at the edge of the groove 15 and the point of this screw enters suitable notches 20 formed in the shoe 18. In the slide 16 is a longitudinal slot 21 65 through which passes the shank of a thumb screw 22 which is screwed into a threaded socket 23 formed in the block which is 10. Extending laterally from the top of the slide 16 is an arm 24 having an opening 25 there- 70 in for the accommodation of drill bushings 26, these bushings being of the ordinary form used with such devices. The bushings are held in position by a set screw 27 or when the form shown in Fig. 5 is used the 75 arm will be provided with two or more openings 25 and a corresponding number of set screws 27, the openings of course receiving each its bushing.

In using the device as a jig several of 80 these V-blocks are employed and in order to hold them in assembled relation a rod 28 is passed through the opening 13 at each block and secured in properly spaced position by means of the set screws 14. One 85 end of this rod projects through one of the openings 13 and on this projecting end is mounted a stop arm 29, the same being held in adjusted position by means of a set screw 30. The upper end of this stop arm is in 90 alinement with the grooves 11 and through this upper end extends a thumb screw 31 provided with a lock nut 32. In Fig. 6 a shaft 33 is shown located in the jig and it will be noted that the arms 24 hold this 95 shaft in the grooves 11 while the screw 31 serves as an abutment or stop for the end of the shaft. It will of course be obvious that the screw 30 provides for coarse adjustment on the bar 28 while the screw 31 provides for the fine adjustment. In order to assist the arms 24 in holding the shaft 33 on the V's a clamp arm is provided which consists of a body portion 34 having an opening 35 therein through which passes 100 the bar 28. From this body 34 extends an arm 36 which passes around one side of the shaft 33 and is provided above said shaft with a thumb screw 37 having a curved and swiveled shoe 38 on its lower end. This 105 clamp is arranged to swing about the bar 28 so that the thumb screw may be alined

over the shaft 33 and upon rotation of this thumb screw the shaft may be clamped securely in the V.

In using a simple V-block the thumb screw 22 is loosed and the shaft placed in the notch or groove 11 after the arm 24 has been raised. The preferable size bushing 26 is secured in the opening 25 and the arm 24 moved down to engage the shaft. The thumb screw 22 is then tightened and the shaft will be firmly locked in position. The device, being set beneath a drill, is ready for the drilling operation. When the drill is moved down the point of the drill enters the hardened bushing 26 and is guided through this bushing to the proper point on the shaft.

When it is desired to drill several holes spaced at predetermined distances the jig shown in Fig. 6 is used. In this case the different blocks are spaced so as to bring the centers of the bushings at the required distance apart. The arm 29 and screw 31 are then adjusted so that when one end of the shaft butts against the screw 31 the first bushing will be centered above the position of the hole to be drilled nearest said end of the shaft. There has thus been provided a simple and efficient device of the kind described and of the character specified.

It will be obvious that many minor changes may be made in the form and construction of this invention without departing from the material principles thereof. It is not therefore desired to confine the invention to the exact form herein shown and described, but it is wished to include all such as come properly within the scope claimed.

Having thus described the invention, what is claimed as new, is:—

1. In a jig, a rod, a plurality of V-blocks slidably mounted on said rod and each provided with a V-shaped groove, the grooves in the secured blocks being alined, means to lock said blocks in adjusted position on said rod, bushing supporting means carried by each of said blocks and arranged to center a bushing over each of the grooves, a stop mechanism mounted on one end of said rod and provided with means for engaging a shaft held in said groove, and a clamp rotatably mounted on said rod and arranged to engage a shaft held in said groove when the clamp is moved to one position.

2. A jig consisting of a plurality of V-blocks each provided with a body having a V-shaped groove and a transverse opening extending parallel to said groove, a rod passing through said opening, and set

screws extending from one side of each block and entering said opening to engage the rod, each of said blocks being provided with a vertically disposed guide way, a slide mounted in said guide way and provided with a longitudinal slot, a thumb screw passing through from each of the said slots into the respective block, an arm extending from each of the slides over the respective grooves, each arm being provided with an opening centrally disposed over the longitudinal axis of the groove, a set screw extending through each arm and engaging a drill bushing in the opening therein and a stop device adjustably mounted on one end of said rod, said stop being provided with a horizontally extending screw adapted to engage the end of a shaft held on said V-blocks.

3. A jig consisting of a plurality of V-blocks each provided with a body having a V-shaped groove on its upper surface and a transverse opening extending parallel to said groove, a rod passing through said opening, and set screws extending from one side of each block and entering said opening to engage the rod, each of said blocks being provided with a vertically disposed guide way, a slide mounted in said guide way and provided with a longitudinal slot, a thumb screw passing through each of the said slots into the respective block, an arm extending from each of the slides over the respective grooves, each arm being provided with an opening centrally disposed over the longitudinal axis of the groove, a set screw extending through one end of said arm, and a clamp swingingly mounted on said rod intermediate two of said blocks.

4. A jig comprising a plurality of V-blocks each consisting of a body having a V-shaped groove on its upper surface and an opening extending parallel with said groove, a rod extending through the openings in said blocks, said blocks being adjustably secured on said rod, arms vertically slidably mounted on said blocks and provided with drill bushings, an arm swingingly mounted on said rod and bent to extend over the axis of the grooves in said blocks, and a swiveled screw clamp on said bent end and adapted to engage a shaft supported on said blocks.

In testimony whereof, I affix my signature, in the presence of two witnesses.

HENRY B. SWANTUSCH.
